UNITED STATES PATENT OFFICE.

CALEB C. DULA, OF NEW YORK, N. Y., ASSIGNOR TO LIGGETT & MYERS TOBACCO COMPANY, OF NEW YORK, N. Y., A CORPORATION OF NEW JERSEY.

PLUG-TOBACCO.

1,365,969.

Specification of Letters Patent. Patented Jan. 18, 1921.

Application filed December 17, 1920. Serial No. 431,367.

To all whom it may concern:

Be it known that I, CALEB C. DULA, citizen of the United States, and resident of New York city, in the county of New York and State of New York, have invented certain new and useful Improvements in Plug-Tobacco, of which the following is a specification.

My present invention relates generally to the manufacture of plug tobacco for chewing and smoking, either or both, and it has for its several objects to provide such a plug with an entirely new "filler" having distinct characteristics possessing marked advantages over the plug fillers heretofore known and now universally found upon the market, and these advantages relate not only to the chewing and smoking properties of the tobacco, but they include also the important item of reduced cost of manufacture.

One object of the invention is to provide a "filler" for plug tobacco wherein the tobacco constituting the filler may be more readily and uniformly blended, and one that will retain its original "condition," *i. e.*, its moisture, flavor and substance, for a greater length of time than plug tobacco composed of tobacco strips or otherwise prepared in usual way.

A still further and important object of the invention is to provide a plug-tobacco filler, which, although densely compressed or compacted permits of sections or slices being readily broken or cut therefrom and which sections or slices may, by simple manipulation, be brought to a loose "fluffy" condition best suited for smoking or chewing.

My improved plug tobacco has other more or less desirable characteristics which will be made apparent in the detailed description to follow.

Briefly and generally stated my new tobacco plug comprises a "filler" mass of "long-cut" tobacco densely compacted into plug, bar or cake form, and a tobacco-leaf wrapper inclosing the filler and compressed thereabout, the whole constituting a plug from which a substantial number of smoking or chewing charges may be removed by the consumer as desired, said removed charge portions being capable of manipulation to bring the shreds thereof into substantially their original "fluffy" condition.

In order to enable others skilled in the art to understand and practise my said in-

vention, I will now proceed to describe the same in detail, reference being made for this purpose to the accompanying drawing; wherein—

Figure 1, is a perspective view of a plug or bar of tobacco made in accordance with the invention, one end thereof being in section to expose the "filler."

Fig. 2, is an enlarged section of a portion of a plug or bar showing more clearly the make-up of the filler.

Fig. 3, is a perspective view of a chewing or smoking charge that has been removed, by cutting, from the plug.

Fig. 4, is a view of the removed charge after it has been rubbed between the hands showing how the filler may be rendered "fluffy" by simple manipulation to place it in condition for smoking in a pipe.

Plug tobacco as now manufactured is generally made from what are known as "strips," *i. e.*, tobacco leaves from which the "stems" or "mid-ribs" have been removed. These are removed either by hand or by machine. Both methods add considerably to the cost of manufacturing the plugs and notwithstanding the care that is usually exercised in preparing the leaves, it is difficult to prevent some stems or stem-parts from finding their way into the finished plugs. This is objectionable, not because the stems do not possess perfectly good smoking and chewing properties when properly prepared, but because they are tough and "woody" in their natural state, and when sections or portions of appreciable length are found in plugs they detract materially from the value of the product.

I have discovered after long and expensive experiments that plug tobacco of superior quality for both smoking and chewing, can be produced by making the "filler" from "long-cut" tobacco and densely compressing or compacting the same into plugs, cakes or bars before the outer leaf wrappers are applied.

By "long-cut" tobacco I mean whole or unstemmed leaves or leaf portions finely cut transversely through the leaf-membrane as well as its stem or mid-rib and branch-ribs, so that the fine strands or threads thus cut from the leaves carry very thin or film-like stem or mid-rib and branch-rib sections, the presence of which, when prepared according to my invention, very materially im-

proves the filler and renders it better and more satisfactory for both smoking and chewing.

I have also discovered that a filler composed of "long-cut" tobacco, when densely compressed or compacted into a plug, cake or bar in accordance with my invention and then inclosed within a tobacco leaf wrapper, retains its "condition" and flavor for a much greater length of time than the "fillers" of ordinary plugs formed from "strips," or otherwise and such long-cut fillers also retain their "condition" much better and longer and are more satisfactory than "loosely" packed cut tobacco such as now found upon the market.

I am aware that it was long ago proposed by patentees early in the art to compress "fine-cut" tobacco in paper and tin-foil cakes; to mold fine-cut tobacco into individual chews; to cut lozenge-like sections from a compressed sheet of tobacco comprising tobacco leaves and an interposed filler of fine-cut tobacco; and to compress coarsely shredded "stemmed" tobacco into leaf-wrapped cakes or plugs; but so far as I am aware none of these proposed products have ever been placed upon the market. This is undoubtedly due to the fact that each of them is deficient or defective for one or more very obvious reasons. At any rate my improved product is clearly distinguishable from those mentioned above, as well as all others of which I am aware, in that the "filler" thereof is composed of "long-cut" tobacco (fine transverse sections of whole leaves or leaf portions, including membrane, and stem or mid and branch ribs) densely compressed or compacted into a cake, plug or bar and inclosed within a tobacco leaf wrapper compressed thereabout; as distinguished from plugs, cakes, lozenges and the like formed from "stemmed" fine cut or shredded tobacco, and the distinction is readily discernible as plugs made according to my invention, when sliced transversely with a knife show very clearly the presence in the filler of the thin, film-like stem and mid-rib sections, which prominently appear as uniformly distributed throughout the darker surrounding plug section formed by the leaf membrane threads or strands.

In manufacturing smoking and chewing plugs according to my invention I first prepare the "filler" from appropriately blended and "cased" or flavored whole leaves or leaf portions which are formed into a so-called "cake." The cake is then cut transversely in very thin slices across the leaves and through the stems or mid-ribs and branch-ribs very much like or resembling "fine-cut" tobacco except that the shreds or fine strands carry thin film-like sections cut from the leaf stems or mid-ribs and branch-ribs, and it is tobacco prepared and cut in this

manner that I term "long-cut." I have discovered that the presence of the thin film-like mid and branch rib sections in the finished "filler" when prepared according to my invention, not only materially reduces the cost of the finished product, because I entirely eliminate the tedious and expensive "stemming" or "stripping" operation, but I have also discovered that such film-like rib sections actually improve the burning properties of the tobacco, give a milder smoke and chew, enable the shreds or strands to be more readily separated so as to be restored to substantially their original "fluffy" condition after having been densely compressed or compacted, and furthermore, they take up or absorb some of the flowing juices or tobacco extracts that exude from the mass under the compressing action and thus become quite or nearly as rich in the tobacco goodness as the membranous parts of the leaves. Indeed I have found that a much better and more uniform blend may be produced from a densely compressed or compacted filler mass of "long-cut" tobacco of the character stated than is possible with any other form of filler with which I am familiar and I attribute this largely to the presence in the filler of the thin or film-like mid and branch-rib sections.

After having been cut as described, the cake slices are treated substantially like the treatment given ordinary "fine-cut" tobacco to bring them into a more or less loose or "fluffy" condition. Any of the approved methods now employed in the manufacture of "fine-cut" tobacco may be utilized to bring about this condition.

In preparing a plug with such a "filler" I take a measured quantity or mass of the prepared "long-cut" tobacco sufficient to form a plug, cake or bar containing a substantial number of smoking or chewing charges, the weight and bulk of the mass depending upon the size of the plug desired. This measured filler mass is then placed in a mold of suitable shape and subjected to a preliminary compressing action which imparts general form thereto, but such preliminary compression is not sufficient to cause the cake or plug to retain its form dimensions. In fact when removed from the mold if left unrestrained, it will slowly swell or expand. Before it has had time to swell or expand to any very great extent however I wrap the cake or plug within a tobacco-leaf wrapper to completely inclose it. The leaf wrapped plug is then subjected to powerful hydraulic pressure to densely compress or compact the filler and closely apply the wrapper thereabout, after which the compressed plug is placed in a finishing press where it is allowed to remain until it has become permanently set, after which it is ready to be packed for the

market. Such a finished plug, except for the fact that a portion has been cut from one end thereof, is illustrated in Fig. 1 of the accompanying drawing, wherein A, designates the tobacco-leaf wrapper; B, the densely compacted filler of "long-cut" tobacco, and C, the film-like mid or stem and branch-rib sections.

The heavy pressure to which the plug has 10 be subjected causes the "long-cut" filler strands to knit together closely and the inherent juices to flow from strand to strand so that a more perfect and uniform blend is secured. This is very important where the 15 filler is made up of different kinds of tobacco, as the juices from one kind of tobacco will flow to and be taken up by another kind and a new blend will thus be formed. This blending action is considerably augmented by the presence in the filler of the 20 thin film-like mid and branch-rib sections because these are very porous and will quickly absorb the exuding juices. Notwithstanding the great pressure to which the 25 filler has been subjected, it is, nevertheless, a simple matter to restore the filler or a removed portion thereof such as shown in Fig. 3, to its original loose and "fluffy" state as shown in Fig. 4, in order to put it in the 30 best possible condition for smoking. This "fluffy" condition may be brought about by simple manipulation of the portion removed. The manipulation may consist of rubbing the portion between the hands or with the 35 fingers as now practised to some extent by pipe smokers in repreparing other kinds of tobacco; or the manipulation may consist in chewing the removed portion, as when the tobacco is used for chewing purposes. In 40 either case the manipulation will restore the densely compacted filler to substantially its original "fluffy" condition and when this takes place during the chewing action it will be found that a soft, smooth and spongy 45 "quid" is provided which gives a delightful chew, notwithstanding the presence in the filler of the film-like cut stem or mid-rib sections. The fact is these sections are so thin that they are substantially as soft and 50 tender as the membranous portions of the leaves themselves and they therefore burn well in a pipe when the filler is smoked and also form a soft, smooth and spongy chew.

The thin film-like stem or mid-rib sections 55 are uniformly distributed throughout the filler mass and are readily distinguishable from the surrounding membranous leaf portions which appear of darker color in the finished plug when the latter is cut 60 through transversely as shown more clearly in Fig. 2. It seems that the presence of the film-like mid-rib sections in the densely compacted filler mass assists materially in the 65 capability of the mass being restored by manipulation to its original "fluffy" condi-

tion. This is probably due to the fact that the sections are not as rich in the gummy constituents of the tobacco as are the leaf membranes and therefore do not adhere or knit so closely at the various points in the 70 mass where they occur. At any rate I consider this as a novel feature of the invention and one that contributes to the success of the product.

My improved plug can be manufactured at 75 less cost than plugs made from "stemmed" or "stripped" tobacco because I am able to eliminate entirely the tedious and expensive stemming or stripping operations, and furthermore because I am able to utilize the 80 whole tobacco leaf, stem and all, which is a very substantial item of saving. Besides these important considerations I have found that the tobacco holds its "condition" for a greater length of time for the reasons stated 85 and in every way affords a better smoke and chew.

While I have shown my improved densely compacted "long cut" filler as being preferably inclosed within a tobacco-leaf wrapper, 90 it is to be understood that the disclosure is not limited to the use of such a wrapper, or to any wrapper at all, for that matter, as the said "filler" itself is considered to be entirely new in the art. 95

What I claim is:

1. Plug tobacco comprising a densely compacted filler of "long-cut" tobacco and a leaf tobacco wrapper. 100
2. A plug or bar of tobacco having a major portion or filler mass of "long-cut" tobacco, and a tobacco-leaf wrapper inclosing the same, the whole being densely compacted into a plug or bar from which a substantial number of smoking or chewing charges may 105 be removed by the consumer as desired, said removed charge portions being capable of manipulation to bring the tobacco shreds into substantially their original "fluffy" condition. 110

3. A plug or bar of tobacco from which a substantial number of chewing or smoking charges may be removed by the consumer as desired, comprising a filler mass of "long-cut" tobacco densely compacted into such a 115 plug or bar, and a tobacco leaf wrapper inclosing the filler and compressed thereabout.

4. A plug or bar of tobacco from which a substantial number of chewing or smoking charges may be removed by the consumer as desired, comprising a filler mass of fine shreds cut transversely from unstemmed tobacco leaves or leaf portions, some of which shreds carry thin film-like stem or mid-rib 125 sections, said filler mass being densely compacted into such a plug or bar, and a tobacco-leaf wrapper inclosing the filler and compressed thereabout.

5. A filler for a plug or bar of tobacco 130

- from which a substantial number of smoking or chewing charges may be removed by the consumer as desired, comprising a mass of "long-cut" tobacco densely compacted
- 5 whereby the stem or mid-rib sections in the mass become substantially impregnated with the tobacco extracts or juices expressed from the membranous portions of the leaves in the compacting action.
- 10 6. The method of making a plug or bar of tobacco from which smoking or chewing charges may be removed by the consumer as desired, which consists in preliminarily compacting a mass of "long-cut" tobacco into
- 15 the form of a plug or bar, loosely inclosing the latter within a tobacco leaf wrapper, and then subjecting the wrapped plug or bar to further and heavier pressure sufficient to densely compact and set the filler, closely
- 20 apply the wrapper thereto, and to cause the

tobacco extracts or juices inherent in the filler mass to flow and impregnate the film-like stem or mid-rib sections forming a part of the filler and thus improve the blend thereof.

25

7. In a method of making plug tobacco, the steps which consist in preliminary forming a mass of "long-cut" tobacco, and subjecting the same to pressure sufficient to densely compact and set the mass and to 30 cause the tobacco extract or juices inherent therein to flow and impregnate the stem or mid-rib sections in the mass, whereby the latter is rendered more uniform in its smoking and chewing properties.

35

Signed at New York city, in the county of New York and State of New York, this 16th day of December, A. D. 1920.

CALEB C. DULA.
